(57) **CLAIM**

The ornamental design for a transition spacer, as shown and described.

DESCRIPTION

FIG. 1 is a front perspective view of the first embodiment of a transition spacer;

FIG. 2 is an exploded perspective view of the embodiment shown in FIG. 1;

FIG. 3 is a front view of FIG. 1;

FIG. 4 is a top view of FIG. 1;

FIG. 5 is a side view of FIG. 4;

FIG. 6 is a bottom view of FIG. 1;

FIG. 7 is an opposite view of FIG. 3;

FIG. 8 is a front perspective view of a second embodiment of a transition spacer;

FIG. 9 is an exploded perspective view of the embodiment shown in FIG. 8;

FIG. 10 is a front view of FIG. 8;

FIG. 11 is a top view of FIG. 8;

FIG. 12 is a side view of FIG. 11;

FIG. 13 is a bottom view of FIG. 8; and,

FIG. 14 is an opposite view of FIG. 10.

The broken lines used in FIG. 1 and FIG. 9 of the drawings disclosure illustrate environment of the transition spacer only and form no part of the claimed design.

1 Claim, 4 Drawing Sheets
